UNITED STATES PATENT OFFICE.

ALFRED WINKLER AND MAX DÜNNEBIER, OF NEUWIED, GERMANY.

DRAWING-IN DEVICE FOR ADHESIVE-APPLYING MACHINES FOR USE IN THE MANUFACTURE OF ENVELOPES.

Application filed October 18, 1921. Serial No. 508,460.

To all whom it may concern:

Be it known that we, ALFRED WINKLER and MAX DÜNNEBIER, citizens of the German Republic, residing at Neuwied, 5 Rhine, Germany, Rheinufer 23 and Engerser Landstrasse 46, respectively, have invented certain new and useful Improvements in Drawing-In Devices for Adhesive-Applying Machines for Use in the Manufacture of 10 Envelopes, of which the following is a specification.

When combining an adhesive-applying machine intended for closing flaps of envelopes and operating after the spreading-out 15 method with a roller folding machine for the manufacture of the envelopes, an unobjectionable working of the drawing-in apparatus is particularly important for obtaining a uniform breadth of the adhesive substance. 20 Drawing-in the sheets of paper must, with such machines, so proceed that the sheets are being drawn-in by jerks, so that they, which overlap each other like roof-tiles, form a continuous web of paper in which the rims 25 of the closing flaps are distant one from the other by the breadth of the coating of the adhesive substance.

Such a drawing-in apparatus is described in the specification forming part of the 30 United States application Serial Number 339,529, filed November 20, 1919, and shown in Figures 5 and 6 of the drawing also forming part of said application. Drawing-in the sheets by jerks is effected in that apparatus by the roller segments 35 10 which co-operate with the roller 4 in the manner there described. If making use of such segments which have been known also already prior to filing the said application, 40 no drawbacks are experienced as long as the single sheets are to be drawn-in immediately in their whole length, without the one being placed upon the other; but if the sheets are to be drawn-in and placed upon one another 45 by jerks, as is the case with the former apparatus in question, the following drawbacks are met with:

There is always one layer of sheets between the segments 10 and the roller 4, the thick-

ness of that layer varying corresponding to 50 the size of the sheets. This whole layer of paper shall be transported, for a certain distinct length of way at every periodic rotation of the roller 4, the rotation lasting as long as the time of contact between the segments and the roller, and the length of that way depending chiefly upon the breadth of the segments 10 and corresponding to the breadth of the layer of the adhesive substance. This transport by jerks for portions of way of equal lengths would succeed if the transport of the web of paper would always commence, as well as cease, exactly with the periodic rotation of the roller 4, but it has been found, and is also explainable 55 if the rather considerable thickness of the layer of paper between the segments and the lower roller is considered, that the rigid segments 10, owing to the pressure they exert upon the layer of paper, cause the web of 60 paper to move before the roller 4 commences to rotate. In the same manner the motion of the paper continues when the roller 4 has already ceased to rotate, because also then a pressure of the segments upon the web of 65 paper exists, viz., until the segments have 70 been moved completely off the paper. There results thus an one-sided moment of motion, that is to say, which acts upon the web of the paper only from above, already before and 75 also after the periodic rotation of the roller 4, whereby displacements within the web of paper are caused and the consequence of which is that the distance between the sheets, as well as the breadth of the layers of the adhesive substance upon the envelopes, becomes 80 ununiform.

Furthermore, if rigid segments are employed, the periodically moved lower roller 4 which operates together with these segments, must be worked with the same rotary speed as said segments because, otherwise, displacements within the web of paper are unavoidable. From this, too great a speed for the periodic motion of the paper 85 results whereby the uniformity and the security of the transport is impaired.

Finally, also the contrivances described

and shown in the United States application 339,529 above mentioned and having the object to change the periodic motion of the paper, behind the rollers 17 and 18, into a continuous one by means of a permanently rotated roller pair 20, 21 have not proved unobjectionable. Experience has shown that the formation of puffs occurring, as a matter of course, between the roller pairs 17—18 10 and 20—21 after every periodic feed motion of the paper cannot be satisfactorily compensated from the permanently rotating roller pair to the next feed motion. Even in the case of most exact determination of 15 the circumferential speed of the roller pair 20—21 there remain now and then small puffs which by and by summarize and grow as great as to cause troubles. Also as disturbing tensions in the paper between the roller 20 pairs 20—21 and 17—18 occur, the cause being the weight of the upper roller 20 and the positive driving means provided for it. This roller and its weight are not sensitive to the 25 tensions occurring in the paper web and not varying according to the thickness of the paper to be worked, and cannot either adapt themselves to these influences, or yield to them.

The present invention now relates to a 30 drawing-in apparatus, the combination and arrangement of parts of which, as well as its manner of operation, corresponds in general to the former United States application above mentioned; but in particular such 35 changes have been made that the before-mentioned drawbacks are overcome. Instead of the rigid roller segments two fingers are made use of, of which each has at its end an easily rotatable roll and which 40 form the members that grasp the paper; they contact (as formerly the segments 10) with the roller 4 at every revolution during the idle running of the machine. As this contact could take place, theoretically, only 45 at one point which would not be sufficient to transport the paper, the fingers carrying the rolls are hinged to their hubs that are located upon the shaft, and they are spring-supported and provided with an adjusting- 50 device in such a manner that their roll-carrying ends are capable of performing any adjustable radial motion. By this is attained that they contact at each revolution with a certain distinct portion of the 55 circumference of the roller 4. Making use of the rolls mentioned instead of the rigid segments offers the advantage that the web of paper present between them and the lower roller 4 can be moved only if this 60 roller rotates because in this case the rollers and the roll form so-to-say a pair of tongs which grasp the web of paper and pull it forward. If, however, the lower roller stands still, the rollers moved over the web 65 of paper rotate upon the fingers, and in roll-

ing along the web they cannot displace either this latter as a whole, or any one of the individual sheets forming it. Every jerk-wise motion of the web of paper must at any rate proceed over the same length of way because the motion of the web depends solely upon the extent of motion of the lower roller. 70

The effect of the drawing-in apparatus is, for the rest, the same as described in the 75 specification of the application No. 339,529. Also in this case a sucking member brings the tip of the lowermost sheet of a pile of paper into the space of action of the drawing-in fingers, or of their rollers respectively, which latter place the tip of the sheet down upon the roller 4 and grasp it and the roller in common and draw the sheet off the pile for a certain length of way. The sucking member now fetches the next 80 sheet and places it upon the preceding one. When drawing-out this latter sheet, all previously drawn-in sheets are also moved for the same length of way so that also here a continuous web of paper is formed, in which 85 the rims of the closing flaps of the individual sheets are equally distant one from the other. 90

By replacing the rigid segments by easily 95 movable rolls is also attained that the periodically moved lower roller 4, and thus also the web of paper, may be given a lesser speed than that of the rolls. For this purpose care must be taken solely concerning the circumstance that during the duration 100 of the periodical motion of the paper the loose rolls exert constantly a pressure against the web of paper to securely effect the transport of this latter, and consequently 105 a longer supporting surface for the web of paper must be provided than the lower roller 4 offers. This is attained by arranging a piece of sheet-metal in front of the lower roller 4. This piece is bent concentrically with respect to the path of the finger 110 rolls and is adjustable with respect to them. The web of paper runs first over this bent piece and only then over the lower roller 4. The finger rolls may thus press against the 115 web of paper along the whole length of the curved portion of the piece of sheet-metal, as well as upon the web of paper. The period of the movement of the paper need now no more fall within the short moment in 120 which the rolls co-operate with the lower roller, but it may extend over the whole length of time, during which the rolls run over the sheet-metal piece and the lower roller. 125

The lastly mentioned drawback concerning disturbances between the last pair of rollers which is permanently moved, viz., rollers of the drawing-in apparatus, has been obviated by substituting for the heavy, 130 positively driven first permanently running

upper roller a comparatively light roll, which runs loosely, i. e., is not especially driven, over the middle portion of the web of paper. At the same time care is taken 5 that this roll may run not only over the first permanently rotated lower roller, but at any desired place between this roller and the next-following strap-drum, whereby it may be so adjusted that it has just grasped the 10 uppermost sheet coming from the periodically feeding system of rollers and having left this latter.

In order to make our invention more clear, we refer to the accompanying drawing which 15 shows, by way of example, one form of construction of a drawing-in apparatus embodying our invention. Figure 1 a side-view of this apparatus, and Figure 2 is a front-view of the lower roller, the drawing-in fingers, and some co-operating parts.

The sheets to be folded are placed upon the frame 1 (which is adjustable for the various sizes) in such a manner that the sucking member 8 is capable of bringing the 25 tip of the lowermost sheet into the scope of the finger rolls 8. A bent piece of sheet-metal *b* is so arranged that the sheets which the sucking member has fetched down are compelled to adapt themselves to the curvature of that piece of sheet-metal. This is important because the sheets which, on the one side, are already grasped by the roller 4 and the rolls 16, but, on the other side, rest 30 partly still under the pile, must always be maintained in uniform tension if an unobjectionable operation of the drawing-in device shall be attained. This is possible only if the sheets are compelled to assume a definitive position between the pile and the 35 roller 4 which is brought about in a compulsory way by laying the sheets against the highly vaulted portion of the piece of sheet-metal in question. This latter is at its upper end downwardly bent, viz., in a circular 40 curve running concentrically with the path of the rotating drawing-in finger *e*, and the rolls *a* attached to them. The object of these contrivances will be dealt with later on.

The construction of the drawing-in fingers *e* and of the rolls *a* which they carry is 50 shown in Figure 2. The shafts *d* which are located above the roller 4 carry at their opposite inner ends the hub parts *e*, to which the drawing-in fingers are hinged. These 55 are angularly formed; the easily rotatable rolls *a* are attached to the horizontal legs of the angles, and the vertical legs are under the pressure of springs *g*; the pressure and the position of the rolls may be adjusted by 60 screws *h*. Each of the shafts *d* carries, near to the hub part *e*, a loosely rotatable roll 16. Also in the construction shown and described in this specification the shafts *d* with the drawing-in fingers *e* are in continuous rotation, whereas the roller 4 rotates 65

periodically for such an extent that measured at its circumference the extent of the motion corresponds to the desired distance between the sheets, within the web of paper. The sheet tips which the sucking member has 70 fetched down are grasped by the rolls *a*, as indicated in Figure 1. During the further rotation of the shafts *d* the rolls press the sheet tip at first against the upper bend of the piece of sheet-metal *b*, and as this bend 75 lies concentrically with the path of the rolls, the pressure of these latter upon the paper continues until the end of that piece. As, furthermore, the rolls *a* proceed from the piece of sheet-metal *b* immediately to the roller 4, and, besides, also the paper lies against this roller, the pressure continues also at this place. As long as the roller stands still, also the web of paper remains 80 at rest, but every motion of the roller 4 is at once transmitted to the web of paper because this, as soon as less sheets have been drawn in, lies between the roller 4 and the loose rolls 16.

The finger rolls *a* which press that sheet 85 which the sucking member has lastly conveyed against the web of paper are, owing to their easy revolvability, only then in the position to move the said sheet (or any of the subsequent sheets), when the web of 90 paper is in motion, because they, if the web of paper is at rest, can make only a relative motion of their own.

The bend of the piece of sheet-metal *a* which extends concentrically to the path of 95 the rolls *a* is important from the following reason:

The rolls *a*, besides having to fetch down the newly arriving sheet, have to convey (solely) also the sheets that have not yet arrived below the rolls 16. Thus, care must be taken that whilst the web of paper is moved, also the sheets lying not yet below the rolls 16 must securely be transported. This can be attained only by the rolls *a* being 100 capable of pressing these sheets firmly against the web of paper lying below them and being formed by the preceding sheets. This, however, is possible only if a solid base, such as formed by the roller 4 and the 105 piece of sheet-metal *b*, is provided for the web of paper. If only the roller 4 would be employed as such a base, one would be compelled to move the web of paper in the short time in which the rolls *a* contact with the roller 4, and the jerk-wise rotation of the roller 4 should, then, proceed with about the same peripheral speed as have the uninterrupted rotating drawing-in fingers. This is the case also with the formerly employed rigid segments where these latter 110 and the roller 4 have the same peripheral speed which, however, concerning the periodical motion of the roller 4 has proved too high because the security and the uniformity 115

of the periodical feed of the paper is thereby impaired.

Concerning, however, the present invention one is in the position to decrease greatly the jerk-wise motion of the roller 4. The rotation of this roller may commence already shortly after the rolls *a* have pressed the sheets against the piece of sheet-metal *b*, and it need cease only shortly before the 10 rolls leave the web of paper above the roller 4. A by far greater security and uniformity of the periodical feed of the paper is thereby warranted. Whilst, where rigid segments are made use of, equal speed of the 15 segments and the lower roller is a fundamental condition, there may be, if the finger rolls are employed, differences of speed of any magnitude, because the difference is automatically completely compensated by 20 the possible relative motion of the rolls.

Between the first lower roller 21 which permanently rotates and the drum 25 is a table-like connection *i*. Over the drum 25, the roller 21, and the table *i*, runs, in the 25 middle portions of these parts, a strap *h*, which, in connection with the loose roll *l*, receives the periodically fed web of paper. The roll *l* is displaceable in the longitudinal direction of the machine and may be adjusted with respect to the size of the sheets, 30 in such a manner, that it grasps the tip of a sheet just when the preceding periodically running rollers are liberating it.

Having now described our invention, 35 what we desire to secure by a Patent of the United States is:

1. A drawing-in device of the kind intended for adhesive-applying machines co-operating with roller folding machines for 40 use in the manufacture of envelopes, comprising, in combination, a sucking member; a periodically rotated lower roller; a loosely rotatable drawing-in roll adapted to revolve like a crank; a member, to the outer end of 45 which said roll is attached; a hub portion having said member hinged to it; and means to limit the extent of motion of the said member in outward direction, substantially as described.

2. A drawing-in device of the kind intended for adhesive-applying machines co-operating with roller folding machines for 50 use in the manufacture of envelopes, comprising, in combination, a sucking member; a periodically rotated lower roller; a loosely rotatable drawing-in roll adapted to revolve like a crank; a piling frame; a piece of sheet-metal forming a continuation of the base of said frame and extending closely to 55 the path of said roll and being bent at its end in a circular curve extending concentrically to said roll path, substantially as described.

3. A drawing-in device of the kind intended for adhesive-applying machines co-

operating with roller folding machines for use in the manufacture of envelopes, comprising, in combination, a sucking member; a periodically rotated lower roller; loosely rotatable drawing-in rolls adapted each to 70 revolve like a crank; members, to the outer ends of which said rolls are attached; hub portions having said members elastically hinged to them; a piling frame; a piece of sheet-metal forming a continuation of the 75 base of said piling frame and extending closely to the path of said rolls and being bent at its end in a circular curve extending concentrically to said roll path; substantially as described. 80

4. A drawing-in device of the kind intended for adhesive-applying machines co-operating with roller folding machines for use in the manufacture of envelopes, comprising, in combination, a sucking member; a loosely running roll adapted to be adjusted in the longitudinal direction of the machine and forming the first permanently running upper roller of the machine; a strap co-operating with said roll; a periodically rotated lower roller; a loosely rotatable drawing-in roll adapted to revolve like a crank; a member, to the outer end of which said roll is attached; a hub portion having said member hinged to it; and means to limit the extent of motion of the said member in outward direction, substantially as described. 90

5. A drawing-in device of the kind intended for adhesive-applying machines co-operating with roller folding machines for use in the manufacture of envelopes, comprising, in combination, a sucking member; a loosely running roll adapted to be adjusted in the longitudinal direction of the machine and forming the first permanently running upper roller of the machine; a strap co-operating with said roll; a periodically rotated lower roller; a loosely rotated drawing-in roll adapted to revolve like a crank; a piling frame; a piece of sheet-metal forming a continuation of the base of said frame, and extending closely to the path of said roll and being bent at its end in a circular curve extending concentrically to said roll path, substantially as described. 100

6. A drawing-in device of the kind intended for adhesive-applying machines co-operating with roller folding machines for use in the manufacture of envelopes, comprising, in combination, a sucking member; a loosely running roll adapted to be adjusted in the longitudinal direction of the machine and forming the first permanently running upper roller of the machine; a strap co-operating with said roll; a periodically rotated lower roller; loosely rotatable drawing-in rolls adapted each to revolve like a crank; members, to the outer ends of which said rolls are attached; hub portions 110

having said members elastically hinged to them; a piling frame; a piece of sheet-metal forming a continuation of the base of said piling frame and extending closely to the 5 path of said rolls and being bent at its end in a circular curve extending concentrically to said roll path; substantially as described.
